CONTROL MEANS

Lewis W. Eggleston and Ernest J. Dillman, Detroit, Mich., assignors to Detroit Lubricator Company, Detroit, Mich., a corporation of Michigan

Application September 28, 1933, Serial No. 691,350

17 Claims. (Cl. 200—81)

Our invention relates to new and useful improvements in control means, and more particularly to a device for use in connection with and for controlling the operation of a mechanical refrigerating system.

An object of our invention is to provide a device by which the average temperature of the space or of the refrigerant evaporator may be regulated or controlled.

10 Another object is to provide means for causing defrosting of the refrigerant evaporator.

Another object is to provide a defrosting control means operable in conjunction with the normal control means for the system to permit automatically reestablishment of the normal refrigerating cycle after the system has been defrosted.

Another object is to provide a safety means for stopping operation of the system in the event that the compressor is overloaded.

20 Another object is to provide means by which the system may be manually started and stopped.

The invention consists in the improved construction and combination of parts, to be more fully described hereinafter and the novelty of which 25 will be particularly pointed out and distinctly claimed.

In the accompanying drawings, to be taken as a part of this specification, we have fully and clearly illustrated a preferred embodiment of our 30 invention, in which drawings—

Figure 1 is a view of our novel control device in front elevation, and having the front cover or closure member removed to show the internal construction;

35 Fig. 2 is a vertical, central section on the line 2—2 of Fig. 4;

Fig. 3 is a detail view in vertical section on the line 3—3 of Fig. 1;

Fig. 4 is a view in vertical section on the line 40 4—4 of Fig. 1, showing the front closure or cover member in place;

Fig. 5 is a detail top plan view of certain manual adjusting means, and

Fig. 6 is a detail bottom plan view in section on 45 the line 6—6 of Fig. 2.

Referring to the drawings by characters of reference, 1 designates, generally, a main casing or housing having a bottom wall 2, end walls 3, 4, and a rear wall 5. The top of the casing is closed 50 by a substantially rectangular plate 6 secured to the casing by screws 7, or the like. Within the casing there is a partition 8 projecting forwardly from the rear wall 5 and having its bottom or underface 9 spaced vertically from the bottom 55 wall 2 and preferably inclined slightly upward

toward the end wall 4, as shown in Figs. 1 and 2. Extending from the partition 8 there is a substantially horizontal partition 10 connecting the same to the end wall 4 and forming with a front vertical partition 11 and with the partition 8 and the casing side walls a compartment or chamber 12. The forwardly extending partition 8 is joined to the end wall 3 by a substantially horizontal partition 13 adjacent the top of the casing. Extending downward from the underside of the bottom wall 2 at the end of the casing adjacent the end wall 3, there is a substantially rectangular, hollow element 14 having a substantially cylindrical, internal bore 15 therethrough and opening upward into the interior of the casing 1. 15

The lower or bottom open end of the bore 15 is closed by a supporting plate or member 16, preferably secured to the element 14 by screws, or the like, 17. Mounted on the supporting member 16 there is a power element or means, designated generally 18, preferably comprising a substantially cylindrical, circumferentially corrugated, expandable-collapsible, resilient element 19, such as a metal bellows, which is secured and hermetically sealed by solder, or the like, at one 20 end, as at 20, to the supporting member 16. The other or upper end of the bellows 19 is closed and sealed by a head member 21 having an externally 25 screw-threaded shank or stem 22 to receive an internally threaded, flanged sleeve 23 providing 30 a guide member and with the flange 24 thereof serving as a stop. The sleeve 23 extends through a guide aperture 25 in a guide and stop plate member 26 fixed to the supporting member 16, the flange 24 cooperating with the member 26 to 35 limit upward movement of the head 21 and expansion of the chamber 27 contained within the power element. Through the supporting member 16 there is a central aperture 27^a which receives one end of a conduit member 27^b, having 40 its other end terminating at and in communication with one end of a substantially cylindrical bulb element 27^c. The other end of the element 27^c is provided with a filling tube 27^d by which the bulb element 27^c and the chamber 27 may 45 be charged with a suitable volatile liquid such as methyl chloride, after which the tube 27^d would be hermetically sealed, for example by solder. Screw-threaded as at 28, or otherwise secured in or to the head 21, there is an upward projecting thrust pin 29 having a substantially conical, pointed end portion. The thrust pin 29 seats in a substantially conical recess or socket 30 provided in a bearing member 31 which is rigidly secured to a lever member 32. The lever mem- 50

55

ber 32 is provided with depending side flanges 33, 34. The lever member 32 is fulcrumed or pivotally supported on a shaft or pivot pin 35 which extends transversely through the flanges 33, 34 and which is supported at its opposite ends in bearing bosses 36, 37 projecting from the end wall 3, which are adjacent and preferably integral with the bottom wall 2. In the top face of the bearing member 31 there is a substantially 10 conical recess or socket 38 which receives the substantially conical, pointed end portion of a thrust member 39 carried by and depending from a spring follower member 40. Seating on the member 40 there is one end of a helical coil spring 41 provided at its other end with a recessed end plate 42 seating against an adjustable abutment member 43, preferably in the form of a screw, threaded and adjustably supported in an internally threaded sleeve 44 secured in and 15 opening through the horizontal partition 43. The spring 41 acts through the lever member 32 to resist operation of the lever member by the power element 18 and determines the force required to be exerted by the power element to 20 actuate the lever member, the spring 41 serving as a range determining means. The lever flanges 33, 34 terminate substantially midway between the casing end walls 3, 4 and are provided at their terminal end portions with top and bottom stop 25 faces 45, 46 respectively which cooperate respectively with the inclined underface 9 and with the top face of the bottom wall 2 to limit the upward and downward throw of the lever member 32. Intermediate the side flanges 33, 34 there is a 30 downward stepped portion 47 which lies beneath the partition 8 and which is spaced laterally from the flanges 33, 34. The end faces of the side flanges 33, 34 which are directed toward the end wall 4 are provided with bearing notches 48, preferably substantially V-shaped, to receive the knife edges 49 of a lever member 50 fulcrumed thereby on the lever member 32. The lever member 50 is provided with an end recess 51 into which the stepped portion 47 extends, and it is 35 also provided with spaced guide fingers 52 which lie between and cooperate with the lever flanges 33, 34 to prevent lateral displacement of the lever members relative to each other and to maintain the knife edges laterally in engagement with their respective bearing notches. Clamped to the 40 top and bottom faces of the lever member 50 there are electric insulating plates 53, 54, preferably rigidly secured thereto by rivets, or the like, 55. Projecting from the side edges of the lever member 50 there are opposite spring supporting arms 56. A pair of toggle springs 57, preferably of the helical coil type, is provided, each having one end secured to one of the arms 56, preferably by hooking the spring end through 45 eyelets provided in the arms. The other ends of the springs 57 are secured to laterally extending, oppositely directed arms 58 projecting from the bottom edges of the lever flanges 33, 34 adjacent the bearing member 31. Positioned between the plates 53, 54 there is a spacer 59 of electric insulating material and through which one of the pairs of rivets 55 is passed. The plates 53, 54 each have a portion projecting beyond the spacer 59 and toward the end wall 4, the projecting portions being of reduced width and designated 60. Vertically through the under portions 60 there is a circular aperture 61 which receives a convex bearing face 62 carried by a transversely extending contact supporting member 63. The supporting member 63 by reason of the convex face

62 has universal movement between the plates 60 and is held in position by means of a rivet, or the like, 64 provided with a convex head seating in a concave recess in the member 63 directly over the convex face 62. The opposite end portions 5 of the supporting member 63 are provided on their underfaces with contacts 65, 66 rigidly secured thereto, as at 67, and electrically connected with each other by means of the member 63 which is of metal, preferably copper. The contacts 65, 19 66 cooperate with contacts 68, 69 carried by terminal posts 70, 71 respectively secured in and projecting through apertures 72 in the bottom wall 2. The posts 70 and 71 are preferably rigidly fixed in position by nuts 73 screw-threaded 15 thereon, and each post is preferably provided with a lead wire clamping a nut 74. Also projecting into the casing 1 through the bottom wall 2 there is a third terminal 75 having a similar binding post nut 76. The external ends of the 20 posts 70, 71 and 75 are enclosed by a cup-shaped cover member 77 having an opening 78 for the passage of the electric lead wires. The post 70 is preferably shielded from the posts 71 and 75 by a partition 79 depending from the bottom 25 wall 2.

Vertically through the partition 8 and directly above the lever member stepped portion 47 there is a cylindrical bore 80 which serves as a guideway for a plunger or thrust member 81 which normally seats on the stepped portion 47. The upper end portion of the bore 80 is of enlarged internal diameter and internally screw-threaded, as at 82, providing an upward facing, annular shoulder 83. The thrust member 81 also has its upper portion of reduced external diameter to provide an upward facing shoulder 84 on which is seated the lower, circumferentially flanged end of a spring follower sleeve 85. Surrounding the sleeve 85 and seating on the circumferential flange thereof, there is a helical coil spring 86 which is held under compression and normally acts to move the thrust member 81 downward. The upper end of the spring 86 seats against a downward facing, annular shoulder 87 formed in 40 an externally threaded sleeve member 88 which is screw-threaded into the threaded bore 82 and which is sleeved on the thrust member 81. Surrounding the upper end of the sleeve member 88 which projects above the partition 8 there is a 45 collar 89 having radial and vertically extended stop faces 90, 91 which cooperate with an abutment 92 carried by the partition 13 to limit rotation of the collar 89. The collar 89 is fixed to the sleeve member 88 by a set screw, or the like, 55 93, see Fig. 3. A circular plate 94 which provides a finger grip for rotating the sleeve member 88 is clamped to the top face of the collar 89 by a sleeve nut 95 which is threaded into the collar 89. The plate 94 is provided on its circumference with a pointed projection 96 which cooperates with suitable indicia 97 carried by the plate member 6 to indicate the direction of rotation of the sleeve member 88 which will result in a lower or colder average temperature in or adjacent the 60 evaporator. The thrust member 81 projects above the clamping nut 95 and is provided on its upper end with a hand engaging abutment 98 by which the thrust member 81 may be moved downward or into the casing. Projecting forward from the 65 partition 11 there is a hollow boss 99 aligned with the partition 8 and containing a detent member 100 reciprocable in a guide bore 101 which opens at its inner end into the bore 80. The inner end of the detent 100 is preferably 75

conical to provide a cam face which cooperates with an inclined face 102 formed on the thrust member 81 for a purpose to be described. Inward movement of the detent 100 is limited by 5 engagement thereof with an outward facing shoulder 103 formed in the guideway 101. A spring 104 seats at its inner end in a cylindrical recess in the outer face of the detent 100 and is held under compression by means of a plug 105 10 adjustably screw-threaded, as at 106, in the enlarged outer end portion of the guide bore 101, such that the spring 104 normally urges the detent 100 inwardly to the limit of its movement. Within the compartment 12 there is a boss or 15 extension 107, preferably integral with the partition 8 and rising from the top face of the partition 10 directly above the lever member 50. In the extension 107 there is a vertical, upward opened, cylindrical recess 108 which communicates at its bottom end through a substantially rectangular slot 109 with the interior of the casing 1 beneath the partition 10. Vertically reciprocable in the slot 109 there is a lever member 20 engaging or governing means 110 which projects downward through an aperture 111 in the lever member 50 and which is provided at its lower end with a lateral extension or arm 112 for engagement with the underface of the lever member 50 for a purpose to be described. The 25 portion of the member 110 which is positioned within the recess 108 is in the form of a hollow rectangle and receives a helical coil spring 113 which is prevented from lateral movement by the walls of the recess 108, and which is held under 30 compression between the bottom of the recess 108 and the horizontal top portion 114 of the member 110 so that the spring 113 normally tends to move the member 110 upward and the arm 112 into engagement with the lever means 50. 35 Through the partition 11 there is a bearing bore 115 in which is journaled a shaft 116, preferably of electric insulating material, such as Bakelite. The bore 115 is of slightly enlarged internal diameter, as at 117, to receive a flange 118 carried by the member 116 to prevent longitudinal 40 movement of the member 116 into the chamber 12. The member 116 is held in its bore by a sleeve member 119 having a polygonal and preferably rectangular flange 120 which seats and is 45 secured in a rectangular recess 121 formed in the outer face of the partition 11. Embedded or otherwise secured in the shaft 116 there is a metallic, cylindrical extension 122 which projects 50 through the sleeve 119 and terminates adjacent the front wall of the casing 1. A pin 123 is passed transversely through the extension 122 and has its end portions in overlying, abutting relation to the free end of the sleeve 29 to hold the portion 120 in its recess 121. Journaled on 55 the shaft 116 within the chamber 12 and in lateral engagement with the inside face of the partition 11 there is an operating lever 124 having a finger engaging portion 125 projecting upward through a slot 126 in the cover member 6 and by which the lever may be oscillated. The lever 60 124 is provided with a finger or arm 127 which overlies and engages the upper end of the operating member 110, the member 110 being held in engagement therewith by the spring 113. Beyond the lever 124, the shaft 115 is provided with a polygonal portion 128, preferably rectangular to receive a star or ratchet-wheel 129 such that the wheel is held against rotation relative to the shaft 116. A pin 130 is passed transversely 65 through the portion 128 to prevent endwise move- 70

ment of the lever 124 and wheel 129. The lever 124 carries a pawl 131 having a tooth 132 engageable with the notches in the ratchet-wheel to normally maintain the lever 124 fixed relative to the shaft 116. The pawl 131 is pivotally carried by a stud 133 rigid with the lever 124 and is normally urged into engagement with the ratchet-wheel by a spring 134 having one end engaging the lever 124 and its other end engaging the pawl 131. The shaft 116 is normally held 10 against rotary movement in the bore 115 by fusible means such as a solder seal between the inner face of the sleeve 119 and the circumferential face of the shaft extension 122. The sleeve 119 is surrounded by a resistance heating coil 135 15 having one terminal connected to the binding post 75 and having its other terminal connected to the binding post 71, the resistance wire having sufficient inherent rigidity so that no support therefor is required to maintain it in the 20 desired position with the coil 135 spaced circumferentially from the sleeve 119. When a two-wire circuit is employed, the binding posts 70 and 75 are electrically connected so that the heating coil 135 is in series circuit with the 25 compressor motor of the refrigerating system.

The operation of our control device is as follows: The bulb element 27^c is preferably positioned adjacent to or within the evaporator or low side element so that the pressure generated 30 by the volatile fluid therein will correspond to the low side temperature. As noted above, the terminal posts 71 and 75 are electrically connected by a suitable lead wire, and the terminal posts 70 and 75 are connected in series circuit 35 with the motor which drives the compressor of the refrigerating system. Assuming that the system is at rest and at room temperature, for example, the parts will be in the positions illustrated in the drawings. If now the line switch 40 to the compressor motor is closed, current will flow through the motor, circuit contacts 68, 65, the supporting bridge member 63, contacts 66, 69, the resistance heating coil 135, to binding post 75, and thence back to line. The compressor will 45 now be operating and as the temperature of the evaporator decreases due to operation of the system, the temperature surrounding the bulb element 27^c will decrease. As the temperature of the evaporator decreases, the pressure of the volatile fluid in the bulb 27^c and therefore in the chamber 27 will also decrease. The force exerted by the volatile fluid in the chamber 27 and which acts to maintain the lever means comprising the lever members 32 and 50 in the position shown 50 will be opposed by the combined forces of the springs 41 and 86. The component of force exerted by the combined toggle springs 51 and transferred to the line of action of spring 41 acts in conjunction with the pressure in the chamber 27 when the lever means is in the position shown to exert sufficient force on lever movement to produce a snap action of the lever 32, that is, on movement of lever 32 the said transferred component of force exerted by springs 51 decreases 55 at a greater rate than the rate at which the force of spring 41 decreases as the toggle point of the levers approaches the line of centers. When the pressure within the chamber 27 plus the said transferred component of force of springs 51 de- 60 creases to a point such that the upward force exerted thereby on the lever member 32 becomes equal to the downward force of the combined springs 41 and 86, then the lever member 32 will move downward. However, substantially at the 65 70 75

time of, but just prior to, movement of the toggle point or point of engagement between the lever members 32 and 50, through the line of centers connecting pivot pin 35 and the switch contacts, the flange of sleeve 85 will engage the upward facing shoulder 83 to stop further expansion of the spring 86, thereby eliminating any further action of this spring through the thrust member 81 upon the lever member 32. Movement of lever 32 up to this point of operation will be gradual. The pressure existing in the chamber 27 must now decrease further before the force exerted by the spring 41 alone will be sufficient to move the toggle point over-center. When the force of the range determining spring 41 acting upon the lever member 32 becomes sufficient to overcome the pressure in the chamber 27, then the continued movement of lever 32 will result from the greater rate of decrease of the component of force of springs 57 as above described, so that the toggle point will be moved quickly to and through the line of centers with a snap action. As the toggle point snaps through center, the toggle springs 57 will snap the lever member 50 upward, pulling the contacts 65 and 66 quickly out of engagement with their respective contacts 68 and 69, thereby breaking the motor circuit and stopping operation of the refrigerating system. Upward movement of the lever member 50 will be limited by engagement of the member 50 with the lever member engaging means 110. The force of the springs 57 will react on the lever member 32 to rotate the same clockwise about the shaft 35 as the toggle point breaks downward, the downward movement of the member 32 being limited by engagement of the stop faces 46 with the inside face of the bottom wall 2. With the compressor at rest, the motor having been stopped, the temperature within and adjacent the evaporator will commence to rise causing expansion of the volatile fluid within the bulb element 27^c and a building up of pressure within the chamber 27. When the pressure within the chamber 27 becomes equal to and slightly exceeds the downward force exerted by the range determining spring 41 plus the downward component of springs 57 transferred to the line of action of spring 41, then the lever member 32 will be moved upward, lifting the point of engagement between the lever members 32 and 50 toward the line of centers. This upward movement will be a quick substantially snap action from initial movement of lever member 32 due to the said transferred component of force decreasing at a greater rate than the rate of increase of force of spring 41 on the lever member 32. Since the lower end of the thrust member 81 stands substantially on the line of centers when the toggle mechanism is broken upwardly, as shown in Fig. 2, it is obvious that the line of centers when the toggle mechanism is broken downward to switch opening position will pass through the thrust member 81 above its lower extremity. Therefore, prior to the toggle point or the point of engagement between the lever members reaching the line of centers, the stepped portion 47 will engage the lower end of the thrust member 81. The pressure within the chamber 27 must now build up sufficiently to overcome the combined resistance of the spring 41 and the spring 86 in order to move the toggle point upwardly over-center. It will therefore be apparent that the spring 86 determines the differential operation of the control device, the greater the tension or downward force exerted

by spring 86 against upward movement of the thrust member 81, the higher the temperature surrounding the bulb element 27^c will have to be in order to move the toggle point over-center so that the toggle springs 57 can move the lever member 50 downward to make contact between the contacts 65, 66 and 68, 69 respectively. When the force exerted on the lever member 32 by the power element 18 becomes great enough to overcome the force of the range determining spring 41 and the differential determining spring 86, then the lever member 50 will be moved downward by the toggle springs 57 with a snap action, the springs 57 reacting on the lever member 32 to snap the same upwardly in a counter-clockwise direction about its fulcrum 35, upward movement of the member 32 being limited by engagement of the stop faces 45 with the inclined underface 9 of partition 8. The refrigerating system will now again be in operation and the temperature in and adjacent the evaporator will decrease with a resulting circuit breaking operation of the control device, as above described. The force of the range determining spring 41 is preferably set at the factory by adjustment of the screw 43 to provide the proper cutting out point for the refrigerating system, that is, to set the low temperature limit of the evaporator. The high temperature limit at which the system will be started or cut in may be manually adjusted by rotation of the plate 94, rotation of the plate 94 in the direction of the arrow, Fig. 5, or counter-clockwise, resulting in a colder or lower average temperature within or adjacent the evaporator. Counter-clockwise rotation of the plate 94 and therefore of the sleeve member 88 will relieve the tension on the spring 86 so that the pressure within the chamber 27 and required to start operation of the system will be less and will be in accordance with counter-clockwise rotation of the plate 94. A stop 92 cooperable with the stop faces 90, 91 rigid with the plate 94 serves to determine the minimum and maximum temperature at which the system may be operated. The function of the spring 86 is to provide what is commonly referred to as a "cold control" for the control device and refrigerating system.

A defrosting control by which the temperature of the evaporator may be raised to a point at which the ice externally collected thereon will melt is provided and functions as follows: When it is desired to defrost the machine or refrigerating apparatus, the plunger or thrust member 81 is moved downward or inward by means of the hand engaging abutment 93. As the thrust member 81 is moved downward, the high point of the cam face 102 will pass beyond or below the high point of the detent 100, the detent moving inward into engagement with the cam face 102 as the high points pass each other, such movement being caused by the compression spring 104. The thrust member 81 may be moved downward irrespective of the position of the lever means, and if the switch contacts are in closed position as shown, the downward movement of the thrust member 81 will carry the toggle point below the line of centers and cause the switch to be opened, thereby stopping the compressor motor. Regardless of whether the switch was in open or closed position when the thrust member 81 was moved inward or downward to effect defrosting of the system, the pressure in the chamber 27 requisite to movement of the switch to closed position will now have to be considerably greater than is required for normal operation as the additional 75

force of the spring 104 acting through the cam surfaces must also be overcome. When the pressure in the chamber 27 has built up sufficiently to force the detent 100 outwardly by the cam action 5 of the face 102, the force exerted by the power element 18 will be sufficient to move the switch to closed position with a continuous, uninterrupted movement as the force is greater than that required to overcome the combined force of 10 springs 41 and 86. When the defrosting temperature has been reached, say 34 degrees F., at which the spring 104 will be overcome, then the parts will move to the position shown in Fig. 3 and the normal operating cycle will be automatically reinstated until such time as the plunger 81 is again moved inward for defrosting of the system.

A combined manual control and automatic electrical overload cut-out or safety device is 20 also provided, and their operation is as follows: Should the compressor motor become overloaded for an appreciable time such as to endanger the motor, the current flowing through the coil 135 will increase. The increased current flow through 25 the coil 135 will raise its temperature sufficiently to heat and melt the solder bond or fusible connection between the sleeve 119 and the shaft extension 122. As the shaft extension 122 is released, the spring 113 will expand as it is no 30 longer opposed and will move the lever member engaging or governing means 110 upward, bringing the arm 112 into engagement with the underside of the lever member 50 with sufficient force to overcome the component of force exerted by 35 the toggle springs 57 and lift the lever member 50 upward about its knife edges to break contact between the contacts 65, 66 and 68, 69 respectively, thereby breaking the compressor motor circuit and stopping the refrigerating system. 40 This upward movement of the engaging means 110 will throw the finger engaging portion 125 of the lever 124 toward the right, facing Figs. 1 and 2, which is the "off" position of the lever 124 and indicates that the system has been either automatically stopped or manually stopped, as will be 45 described. The system may be again started by manual movement of the lever 124 through the medium of the portion 125, by movement of the portion 125 manually toward the left, facing Figs. 50 1 and 2. As the lever is moved counter-clockwise, or to the left as above stated, the pawl 131 will ride over the adjacent projection on the ratchet-wheel and snap into position in the next notch, taken in a counter-clockwise direction facing Fig. 55 2, which will result in a movement of the arm 127 to the position shown in Fig. 2. Movement of the arm 127 to the position of Fig. 2 can only be effected by compression of the spring 113 and downward movement of the lever engaging means 60 110 to the position shown, which will release the lever member 50 and permit the toggle springs 57 to close the switch in the event the temperature in or adjacent the evaporator is at or above the maximum desired degree. The foregoing re- 65 setting of the switch mechanism is, of course, dependent upon solidification of the melted solder to reestablish the bond between the sleeve 119 and the shaft portion 122, otherwise the ratchet-wheel 129 would rotate with the lever 70 124 and not hold against the force of spring 113 upon release of the finger engaging portion 125. Should it be desired to stop the system manually, the lever 124 may be rotated clockwise of Fig. 2 by the finger engaging portion 125. Since the 75 lever 124 is journaled on the shaft 115, it may be

rotated when sufficient force is exerted to cam the pawl 131 outward against the force of the pawl spring 134. This manual movement of the lever 125 in a clockwise direction will lift the arm 127, permitting the spring 113 to expand and lift the arm 112 into contact breaking engagement with the lever member 50. The switch may be closed after manual opening of the same by movement of the lever 124 in a counter-clockwise direction upon the exercise of sufficient force both to cam the pawl 131 outward and into its next adjacent notch and to overcome the force of spring 113.

What we claim and desire to secure by Letters Patent of the United States is:

1. A control device of the character described, comprising a control means, lever means for actuating said control means, a power element for moving said lever means in one direction, means resisting operation of said element, a thrust 20 member operable on said lever means, means cooperable with said resisting means and acting through said thrust member to oppose operation of said element, means to adjust the opposing force of said last-named means, and means engageable with said thrust member for increasing the resistance to operation of said element without increasing the resisting force exerted by said first-named cooperable means.

2. A control device of the character described, comprising a control means, lever means for actuating said control means, a power element for moving said lever means in one direction, means resisting operation of said element, a manually movable thrust member operable on said lever 35 means, means cooperable with said resisting means and acting through said thrust member to oppose operation of said element, and means cooperable with said thrust member upon manual movement thereof toward said lever means for increasing the resistance to operation of said element which is exerted by said first-named cooperable means.

3. A control device of the character described, comprising a control means having two positions 45 of rest, a lever member having a fulcrum support, a power element for moving said lever member in one direction to move said control means to one of said positions, means resisting operation of said element and operable to move said control means to the other of said positions, a second lever member operatively connecting said control means to said power element and said resisting means and pivotally supported by said first-named lever member, spring means acting 55 on said second-named lever member and operable upon movement of said first-named lever member to move said second-named lever member, means to hold said control means in one of said positions, and means acting on said first-named lever member to oppose operation of said element.

4. A control device of the character described, comprising a control means, a lever member having a fulcrum support, a power element for moving said lever member in one direction, means resisting operation of said element, a second lever member for actuating said control means and pivotally supported by said first-named lever member, spring means acting on said second-named lever member and operable upon movement of said first-named lever member to move said second-named lever member, means acting on said first-named lever member to oppose operation of said element, and temperature respon- 75

sive safety means cooperable with and acting on said second-named lever member to actuate said control means.

5. A control device of the character described, comprising an electric switch, a lever member having a fulcrum support, a power element for moving said lever member in one direction, means resisting operation of said element, a second lever member for actuating said switch and pivotally supported by said first-named lever member, spring means acting on said second-named lever member and operable upon movement of said first-named lever member to move said second-named lever member, means acting on said 10 first-named lever member to oppose operation of said element, an electric resistance element in circuit with said switch, and means responsive to temperature created by said resistance element to move said switch to open position.

20. 6. A control device of the character described, comprising an electric switch, a lever member having a fulcrum support, a power element for moving said lever member in one direction, means resisting operation of said element, a second lever member for actuating said switch and pivotally supported by said first-named lever member, spring means acting on said second-named lever member and operable upon movement of said first-named lever member to move said second-named lever member, a reciprocal thrust member cooperable with said first-named lever member, a spring acting upon movement of said thrust member by said first-named lever member to oppose operation of said element, said thrust member being manually operable to move said switch to open position, and means operable upon manual movement of said thrust member to resist movement of said thrust member by said first-named lever member whereby to increase the force of said power element necessary to close said switch.

7. A control device of the character described, comprising an electric switch, a lever member having a fulcrum support, a power element for moving said lever member in one direction, means resisting operation of said element, a second lever member for actuating said switch and pivotally supported by said first-named lever member, spring means acting on said second-named lever member and operable upon movement of said first-named lever member to move said second-named lever member, a reciprocal thrust member cooperable with said first-named lever member, a spring acting upon movement of said thrust member by said first-named lever member to oppose operation of said element, said thrust member being manually operable to move said switch to open position, means operable upon manual movement of said thrust member to resist movement of said thrust member by said first-named lever member whereby to increase the force of said power element necessary to close said switch, an electric resistance element in circuit with said switch, means responsive to temperature created by said resistance element to move said switch to open position, said last-named responsive means having means cooperable with said second-named lever member and operable to overcome said spring means, and manual means cooperable with said last-named means to move said switch to closed position upon movement of said switch to open position by said last-named responsive means.

8. A control device of the character described, comprising an electric switch, a lever member

having a fulcrum support, a power element for moving said lever member in one direction, means resisting operation of said element, a second lever member for actuating said switch and pivotally supported by said first-named lever member, spring means acting on said second-named lever member and operable upon movement of said first-named lever member to move said second-named lever member, a reciprocal thrust member cooperable with said first-named lever member, a spring acting upon movement of said thrust member by said first-named lever member to oppose operation of said element, said thrust member being manually operable to move said switch to open position, means operable upon manual movement of said thrust member to resist movement of said thrust member by said first-named lever member whereby to increase the force of said power element to close said switch, an electric resistance element in circuit with said switch, means normally acting to move said switch to open position, and fusible means responding to rise of temperature created by said resistance element to release said last-named normally acting means.

9. A device of the character described, comprising a control means having two positions, a toggle mechanism including a lever and an arm fulcrumed thereon, said arm being operatively connected to said control means to move said control means to one or the other of said positions upon movement overcenter, a movable resistance member having a portion engageable by said lever, means urging said resistance member portion to a position intermediate the lines of centers of said toggle mechanism, said resistance member being engaged by said lever on movement in one direction prior to movement overcenter to oppose movement of said toggle mechanism in said one direction, and means to limit movement of said resistance member by said urging means short of overcenter movement of said toggle mechanism in the opposite direction such that said resistance member will be ineffective to urge said toggle mechanism overcenter in said opposite direction.

10. A device of the character described, comprising a control means having two positions, a toggle mechanism including a lever and an arm fulcrumed thereon, said arm being operatively connected to said control means to move said control means to one or the other of said positions upon movement overcenter, a movable resistance member having a portion engageable by said lever, means urging said resistance member portion to a position intermediate the lines of centers of said toggle mechanism, said resistance member being engaged by said lever on movement in one direction prior to movement overcenter to oppose movement of said toggle mechanism in said one direction, means to limit movement of said resistance member by said urging means short of overcenter movement of said toggle mechanism in the opposite direction such that said resistance member will be ineffective to urge said toggle mechanism overcenter in said opposite direction, and means cooperable with said resistance member to increase the opposition to movement of said toggle mechanism in said one direction.

11. A device of the character described, comprising a control means having two positions, a toggle mechanism including a lever and an arm fulcrumed thereon, said arm being operatively

- connected to said control means to move said control means to one or the other of said positions upon movement overcenter, a movable resistance member having a portion engageable by said lever, means urging said resistance member portion to a position intermediate the lines of centers of said toggle mechanism, said resistance member being engaged by said lever on movement in one direction prior to movement overcenter to oppose movement of said toggle mechanism in said one direction, means to limit movement of said resistance member by said urging means short of overcenter movement of said toggle mechanism in the opposite direction such that said resistance member will be ineffective to urge said toggle mechanism overcenter in said opposite direction, and means cooperable with said arm to move said control means relative to said lever.
12. In a device of the character described, an operating lever, a control means operable by said lever, a thrust member longitudinally reciprocal in the plane of movement of said lever and engageable thereby, a spring urging said thrust member into position for engagement by said lever such that said spring will oppose movement of said lever in one direction, means to limit movement of said thrust member by said spring in the opposite direction such that said lever is moveable out of engagement with said thrust member, means to actuate said lever, and means to hold said control means in inactive position irrespective of actuation of said lever by said last-named means.
13. In a device of the character described, an operating lever, a control means operable by said lever, a thrust member longitudinally reciprocal in the plane of movement of said lever and engageable thereby, spring means urging said thrust member into position for engagement by said lever such that said spring means will oppose movement of said lever in one direction, means to limit movement of said thrust member by said spring means in the opposite direction such that said lever is moveable out of engagement with said thrust member, means operable without increasing the force exerted by said spring means and cooperable with said thrust member to increase the resistance of said thrust member to movement of said lever in said one direction, and means to actuate said lever.
14. In a device of the character described, an operating lever, a control means operable by said lever, a thrust member longitudinally reciprocal in the plane of movement of said lever and engageable thereby, a spring urging said thrust member into position for engagement by said lever such that said spring will oppose move-
- ment of said lever in one direction, means to limit movement of said thrust member by said spring in the opposite direction such that said lever is moveable out of engagement with said thrust member, said thrust member being movable beyond said limit of movement, means operable upon such movement of said thrust member to increase the resistance of said thrust member to movement of said lever in said one direction, and means to actuate said lever.
15. A control device of the character described, comprising an electric switch, a lever member having a fulcrum support, a power element for moving said lever member in one direction, means resisting operation of said element, a second lever member for actuating said switch and pivotally supported by said first-named lever member, spring means acting on said second-named lever member and operable upon movement of said first-named lever member to move said second-named lever member, means acting on said first-named lever member to oppose operation of said element, an electric resistance element in circuit with said switch, a spring under stress and tend-in to move said switch to open position, releasable means holding said spring against movement, and means responsive to temperature created by said resistance element to release said releasable means so that said last-named spring can open said switch.
16. In a device of the character described, a control means movable from and to predetermined positions, automatically acting means operatively connected to and for actuating said control means, governing means for moving said control means to one of said positions in opposition to said automatically acting means, said governing means comprising a slide member, means acting to move said slide member, a movable member having a stop position for holding said last-named means against actuation, fusible material securing said movable member in said stop position, and a heating means for fusing said material.
17. In a safety device, a supporting member, a tubular element mounted on said member and held against movement about its longitudinal axis, a rotatable member journaled in said element and projecting therefrom, fusible material securing said rotatable member to said tubular element, an operating element stressed for movement in one direction, means operable by said rotatable member and opposing movement of said operating element, and heating means for fusing said fusible material so that said operating element can move.
